(74) *Attorney, Agent, or Firm* — Ann K. Gallagher

(57) **CLAIM**

The ornamental design for a hook, as shown and described.

DESCRIPTION

FIG. 1 is a perspective view showing a new design for a hook;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof;

FIG. 8 is a perspective view showing another embodiment of the new design for a hook;

FIG. 9 is a front view thereof;

FIG. 10 is a left side view thereof;

FIG. 11 is a right side view thereof;

FIG. 12 is a rear view thereof;

FIG. 13 is a top view thereof; and,

FIG. 14 is a bottom view thereof.

The portions of the hook depicted in broken lines form no part of the claimed design.

1 Claim, 6 Drawing Sheets
